UNITED STATES PATENT OFFICE

ALOISE GALL, OF ORANGE, NEW JERSEY, ASSIGNOR TO CYRUS CLARK CO., INCORPORATED, OF NEW YORK, N. Y.

DESIGN FOR A TEXTILE FABRIC OR SIMILAR SHEET MATERIAL

Application filed May 1, 1931. Serial No. 39,676. Term of patent 3½ years.

To all whom it may concern:

Be it known that I, ALOISE GALL, a citizen of the Republic of France, residing at Orange, in the county of Essex and State of New Jersey, have invented a new, original, and ornamental Design for Textile Fabric or Similar Sheet Material, of which the following is a specification, reference being had to the accompanying drawing, forming part thereof.

The figure is a plan view of a textile fabric or similar sheet material, showing my new design.

I claim:

The ornamental design for a textile fabric or similar sheet material substantially as shown.

ALOISE GALL.
